GAME DEVICE

Soren M. Klyver, Los Angeles, Calif.

Application November 28, 1947, Serial No. 788,596

8 Claims. (Cl. 273—35)

1

This invention relates to a game device and more particularly to an indoor game having analogy, particularly as to scoring calculations, to the outdoor game of golf.

In one embodiment of my invention, the game may be played by use of an ordinary golf club which is employed to strike a golf ball mounted upon a crank arm of my game device; the motion imparted to the golf ball of the device being conveyed by suitable mechanism to the scoring member of the game. In a preferred form, scoring is accomplished by a rolling indicator ball mounted on a radial arm so as to follow an annular path bearing suitable scoring indicia.

Other objects and advantages of the invention will be apparent from the following description and claims, the novelty consisting in the features of construction, combination of parts, the unique relations of the members and the relative proportioning, disposition, and operation thereof, all as more completely outlined herein and particularly pointed out in the appended claims.

In the drawings, which form part of the present specification:

Fig. 1 is a perspective view, as seen from above, of the embodiment of my game device which is adapted to be placed on the floor of a room and operated by means of a golf club or the like, which is employed to strike the golf ball disposed upon the crank arm projecting from the side of the device;

Fig. 2 is a vertical axial sectional view taken thru the device along the line 2—2 of Fig. 1 with the crank member and radial scoring arm shown in elevation;

Fig. 3 is a vertical, sectional view partly in elevation, taken at right angles to the section of Fig. 2 along the line 3—3;

In the embodiment illustrated in Fig. 1, there is provided a generally rectangular box-like structure 10 having a flat, generally horizontal top 12 and bottom 14 spaced apart by four side walls 16 disposed at right angles to each other so as to describe a square. Within the box there is fixedly mounted a right angle bracket member 18, the opposite ends of which are secured to the side and bottom of the box respectively by tabs 20 and 22 held by screws or staples. Accordingly, the bracket presents a horizontal arm 24 spaced below and parallel to the top 12 and extending inward from one side 16—a little beyond the center of the box where it is turned down to form the upright supporting arm 26.

For operation, there is provided a crank arm

2

28 having a horizontal portion 30 rotatably journaled successively in the side wall 16—a, the bracket tab 20, and the upright arm 26 of the bracket 18. Outside the wall 16—a, the horizontal portion 30 of the crank arm is bent at right angles to provide a vertical arm 32 which at its extremity is bent outward parallel to the segment 30 to form a short extension 34. A golf ball 36 is provided with a transverse bushing 38 by means of which it is retained freely rotatable upon the crank extremity 34 in a position such as to be just vertically suspended above the floor when the vertical arm 32 extends downward.

Upon the upper face of the top 12, there is inscribed an annular band or ring 40 provided with radially directed segments 42 bearing a sequence of numbers, here shown as 1 to 18. At the center of the band there is provided a bearing structure 44 consisting of a lower plate 46 mounted below the top 12, and an upwardly extending collar 48 which projects thru and extends a short distance above a corresponding aperture in the top. A horizontally disposed, radial arm 50 is located above the top 12 with an inner, turned-down end 52 and rotatably mounted in a corresponding aperture of the bearing structure 44, which after projecting below the bearing plate 46 is again bent oppositely at right angles or substantially parallel to the upper arm 50 to provide a horizontal extension 54 which is disposed to be contacted by the upstanding end 56 of the crank arm.

The free arm of the radial arm 50 overlies the annular band 40 of indicia and is provided with a rotatable ball 58 disposed in rolling registration with said band so that upon rotation of the arm 50 on its pivot arm 52, the ball 58 will roll along the path 40 and stop upon one or another of the numbers or other indicia inscribed thereon. A centrally apertured, horizontally disposed disk 60 is located upon the top 12 of the box with its under face in juxtaposition therewith and its axial aperture receiving the bearing collar 48 therethru. An annular band 62 upon the upper face of the disk 60 adjacent the outer edge thereof is divided into radial segments similar to the segments 42 of the band 40 and alignable therewith at successive stations of rotation of the disk, the several segments 64 of the disk carrying indicia related to those in the outer band 40.

On the outer face of the side 16—a, there is mounted an outwardly projecting catch 66 which is provided with a pair of resilient diverging arms

68 and 70 disposed in alignment with the crank arm 42 so that upon the ball 36 being struck, the arm 32 will be received between and retained by the arms, as illustrated in broken lines in Fig. 1. Such movement of the crank causes its inner, upright contact arm 56 to strike the horizontal arm 54, thus spinning or rotating the radial arm 50 together with its indicator ball 58. During rotation of the radial arm 50, however, the crank arm 32 will be retained by the catch 66 so that its contact arm 56 now held in turned-down position as shown in broken lines in Fig. 3 will not interfere with the free rotation of the under arm 54 of the spinning indicator 50. Upon the indicator ball 58 coming to rest upon a number on the band 40, the crank arm 32 may then be easily disengaged by simple contact from between the resilient catch arms 68 and 70, and the golf ball 36 returned to its lowermost position from which the player may again strike it with a golf club or the like.

The band 40, as noted earlier, is marked with the numbers 1-18 in sequence, corresponding to the 18 holes of a golf course and the object of the present game device is for each player to make the indicator ball 58 stop upon the numbers 1 to 18 in sequence with as few strokes as possible being taken to reach each number. The inner, rotatable disk 60 is intended to carry numbers indicating the number of strokes accepted as par on each individual position along the outer band 40. Thus, as illustrated, the par number of strokes to get to position No. 1 on the outer band is one; par for position No. 2 is six; par for position No. 3 is 4; etc.

In other words, the player should try to get the indicator ball 58 to stop on position No. 1 by one stroke; he should try to get it to stop upon position 2 with six strokes; on position 3 with four strokes; and so on. The players take turns at hitting the golf ball 36 and a maximum of say six or eight strokes is allowed each player before the following player has his turn. The total number of strokes which each player requires to land the indicator ball 58 upon each of the 18 positions in sequence is computed and the player having the lowest number is the winner. If a player obtains any position in less than the number of strokes listed for par, he can subtract the difference in strokes from his total score. The reason for having the center disk 60 rotatable is so that the par number for each playing position may be changed at will, that is, from one game to another.

While I have shown and described in some detail a presently preferred embodiment of my indoor game, it is to be understood that various modifications may be made in the construction and operation thereof within the spirit and scope of the subsequently claimed invention which is to be construed broadly.

I claim:

1. A game device comprising: a surface bearing scoring indicia arranged in an annular path; a radial arm, said arm being mounted to rotate about a pivot disposed intermediate the ends of the arm and being provided with an offset adjacent said pivot, said arm extending toward said path from the center thereof and mounted for pivotal movement about said center; and operating means for rotating said pivoted arm, said means comprising a crank lever mounted so as to swing in a generally vertically plane and having a free end thereon, the other end of said crank

lever being offset, said offset being of sufficient length to contact the offset on said radial arm.

2. The device of claim 1 wherein said operating means comprise: a lever rotatably journaled in said device, one end of which is disposed to strike the inner end of said radial arm so as to cause the outer end thereof to travel along its orbit adjacent said path, and a ball mounted on the other end of said lever and adapted to be struck by a golf club so as to cause said lever to strike the radial arm.

3. A game device comprising: walls defining a structure adapted to be placed on a floor and having a substantially horizontal top surface 15 spaced above the floor, which surface bears scoring indicia arranged in an annular path about its upper face; a radial arm extending toward said path from the center thereof and mounted for pivotal movement about said center; a rotatable member disposed on the outer end of said arm in rolling registration with the top along said path; a crank arm rotatably journaled in the side of said structure, one end of which is disposed to strike the inner end of said radial arm 25 so as to rotate the same; a ball mounted on the other end of said crank so as normally to be disposed adjacent the floor; and a catch mounted on said structure in line with said crank arm and adapted to yieldingly engage the same when the 30 crank arm is turned by said ball being struck.

4. The device of claim 3 which contains a rotatable disk concentrically mounted in relation to said annular path, the outer periphery of said disk being spaced inwardly from said rotatable member, said disk being rotatable to selected stations about said path, which disk bears scoring indicia related to and alignable with the indicia of said annular path.

5. The device of claim 1 which contains a rotatable member disposed adjacent the outer end of said radial arm in rolling registration with said surface along said annular path.

6. A game device comprising: a surface bearing scoring indicia arranged in an annular path; a radial arm, extending toward said path from and over the center thereof and mounted for pivotal movement about said center; a crank lever having a sphere on one end adapted to be struck by a golf club; and connecting means disposed beneath said surface for transmitting movement of said lever to said radial arm so as to rotate the same upon said sphere being struck.

7. A game device comprising: a surface bearing scoring indicia arranged in an annular path; a radial arm, extending toward said path from the center thereof and mounted for pivotal movement about said center; a normally vertically disposed lever operatively connected to the radial arm for propelling the same and disposed to be swung in a limited arc; and retaining means for yieldingly holding said lever in an upswung position upon its being struck.

8. A game device comprising: a surface bearing scoring indicia arranged in an annular path; a radial arm, said arm being mounted to rotate about a pivot disposed intermediate the ends of the arm and being provided with an offset adjacent said pivot; a ball carried upon the end of said arm adapted to rotate along said annular path; operating means for rotating said arm, said means comprising a crank lever mounted so as to swing in a generally vertical plane and having a free end thereon, the other end of said crank lever being offset, said offset being of sufficient length to contact the offset on said radial arm; and a rotat-

able disk concentrically mounted within the inner periphery of said annular path and rotatable to selected stations about said path, which disk bears scoring indicia related to and alignable with the indicia of said annular path.
